CLAIM

The ornamental design for a detachable pocket for semiconductor test socket housing as shown and described.

DESCRIPTION

FIG. 1 is a top, front, and left-side perspective view of a detachable pocket for semiconductor test socket housing, showing my new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof; and,

FIG. 7 is a bottom view thereof.
